METHOD OF FINISHING SHOE HEELS
Ben V. Dardig, New York, N.Y., assignor to United Dynamics Corporation, New York, N.Y., a corporation of New York

Filed Sept. 25, 1962, Ser. No. 226,125
17 Claims. (Cl. 12—147)

This invention relates to improvements in shoe manufacture and is more particularly addressed to a method of contouring and sizing the heels of shoes using so-called snap-on heels.

As conducting to a proper understanding of the present invention, reference is had to my Patent No. 2,932,099, dated April 12, 1960, entitled "Detachable Heel," which discloses and claims a snap-on type of detachable heel construction for shoes, particularly but not exclusively men's shoes, which comprises a heel base affixed to the heel seat portion of the shoe outsole and an outer heel which is adapted to be snapped on to the heel base by means of complementary stud and socket-type separable fasteners carried by said heel base and heel, respectively, on the respective interfaces thereof. In addition to the obvious advantage provided by such a heel construction in respect to replacing a worn heel, for example, continuing experience with the snap-on heel construction according to my aforesaid patent has demonstrated that it also possesses the far greater advantage not only in rendering the heels of the same pair of shoes interchangeable with one another so that they may be switched about when only partly worn, for example, but also of rendering a heel interchangeable with any heel of a shoe of any make using the same size heel. Stated in other words, the snap-on heel concept of my patent aforesaid has opened up new possibilities not only as respects the interchangeability of the heels of the same pair of shoes but also of establishing, for the first time, the universal interchangeability of shoe heels, regardless of make.

However, prior to my present invention there was available no machinery or known procedure for so contouring and sizing an entire shoe heel, i.e. the heel seat portion of the insole, the heel base and the outer heel (the latter sometimes also referred to as the heel tread or heel lift), permitting the aforesaid possibility of true heel interchangeability to be realized. On the other hand, the accepted practice in shoe heel contouring or trimming and sizing was to nail the heel base and heel proper in that order to the heel seat of the shoe outsole and then trim and scour all three heel components by hand, a practice resulting in uneven contouring and differences in size to a degree making heel interchangeability impossible. Although the patent literature contains record of efforts made by workers in the field of shoe manufacture in the direction of trimming heels by machine means, for example, Mayo Reissue Patent No. 11,770, dated September 5, 1899, and Winkley No. 1,529,047, dated March 10, 1925, such do not and cannot possibly result in universal or even heel-pair interchangeability, because of their failure in establishing, in the first instance, any definite shape, size and contour which can act as a master pattern, through the use of which heels may be contoured and sized with the exactitude required for both pair and universal interchangeability as aforesaid.

Thus, stated broadly, a major object of the present invention is the provision of a method of trimming and more particularly, of contouring and sizing the heels of shoes in such manner as not only to render the outer heel, i.e. lift or tread portion, of any particular pair of shoes interchangeable with respect to one another but also to render either one of said heels interchangeable with

2

any heel of a shoe of any make using the same size heel.

A more particular object of the invention is to provide a method of so contouring and sizing the heel seat and heel base of a shoe heel to one of a series of standard sizes and shapes that will accept a snap-on outer heel, preferably of the type disclosed and claimed in my aforesaid patent, as will enable such an outer heel to be attached to either the right or left shoe of a particular pair thereof for interchangeable use thereon, as well as to any shoe of a pair within the size range which will use the same size heel, thus establishing universal interchangeability of heels with respect to all shoes within said size range.

Another object of the invention is the provision of a method of exactly contouring and sizing the heel seat and heel base components of shoes to any selected one of a series of standard sizes and shapes of finished snap-on heel suitable thereto, through the use of a template which is an exact replica of the snap-on heel to be attached and which itself is adapted to be temporarily snapped onto the shoe heel or heel seat portion of the outsole, in position such that it is effective to serve as a pattern for the contouring and sizing means employed.

Yet another object of the invention is the provision of a method of contouring and sizing shoe heels, based on the use of a template serving as a pattern of the exact size, shape and contour to which the heel seat and heel base components of a shoe heel must be trimmed to enable an outer finished heel component which is interchangeable with respect to that of an opposite shoe of a pair; and also to the heel of any shoe using the same size heel, to be attached thereto.

A further object of the invention is the provision of a method as last stated applied to shoes using snap-on heels, wherein the template may be simply snapped onto and unsnapped from the heel base component, thus to provide a simple, practical and fast method of template attachment and detachment which reduces to a minimum the machine-out time and lag likely to occur with use of a template.

The above and other objects and features of advantages of the invention will appear from the following detailed description of the heel contouring and sizing method and implementing apparatus as herein proposed and provided, taken with the accompanying illustrative drawings, wherein—

FIG. 1 is a fragmentary perspective view of a shoe having a heel base for a snap-on-heel applied thereto and prior to any contouring and sizing of the heel seat and heel base components of the heel;

FIG. 2 is a perspective view looking onto the attaching face of an interchangeable (right or left) snap-on heel of finished contour and size adapted according to the invention to be snapped on to the heel base of the shoe shown in FIG. 1;

FIG. 3 is a perspective view looking on to the attaching face of a metal template contoured and sized exactly as the heel shown in FIG. 2 and which, when attached to the heel base shown in FIG. 1, is adapted to serve as a standard or pattern establishing the contour and size of the heel seat and heel base components shown in FIG. 1;

FIG. 4 is a broken-away side elevation intended to illustrate the template shown in FIG. 3 temporarily attached to the heel base of the shoe shown in FIG. 1, the latter being thus ready for the heel seat and heel base contouring and sizing operation;

FIG. 5 is a section taken along line 5—5 of FIG. 4;

FIG. 6 is a broken-away, part-sectional side elevation of a preferred form of heel trimming or contouring and sizing apparatus according to the present invention, and which further illustrates the manner of using the template shown in FIGS. 3 and 4 as a heel trimming guide;

FIG. 7 is a view generally similar to FIG. 6 but in which heel scouring means has been substituted for the trimming and contouring means shown in FIG. 6; and

FIG. 8 is a fragmentary plan view illustrating the constructional and mounting details of the sanding belt or band forming a part of the aforesaid scouring means.

According to the invention, a shoe 10 (FIG. 1) of a construction adapting it to use a snap-on heel such as disclosed and claimed in my aforesaid prior Patent No. 2,932,099 is provided in a preliminary operation with a heel base 12 affixed to the heel-seat portion 14 of its outsole 16 as by nails 18, said heel base carrying a plurality (three being illustrated) of male fastener elements (studs) 20 arranged one towards the rear of its longitudinal center line and the other two symmetrically to the sides of said center line and in the heel corner areas as shown. At this stage of heel manufacture, both the heel base 12 and the heel-seat portion 14 of the outsole are only roughly contoured and are oversize, as indicated by the stippling.

On the other hand, the snap-on heel 22 (FIG. 2), ultimately to be attached to said heel base 12 and which is accordingly provided with embedded socket-type fastener elements 24 complementary to and arranged similarly to the aforesaid studs 20, is fabricated and supplied not only as an exactly and finally contoured finished item but also with identical right- and left-half configuration and size enabling it to be attached to either shoe of any particular pair thereof, thus to be interchangeable with the heel of the other shoe of said pair, and/or to any shoe of pairs thereof using the same size of heel. Such exact contouring and sizing of the snap-on heel 22 is readily attainable by, in the case of rubber or composition (including the plastics suitable for a shoe heel) type heels or, in the case of leather or leather-type heels, by die-cutting or fabricating said heel to the exact standard size and contour. It is to be understood that the fastener sockets 24 are properly positioned (embedded) in the heel during the course of the heel molding or fabricating operation so that their working ends are accessible through the inner or attaching face of said heel.

Because of the likelihood of a finished outer heel corresponding to the aforesaid snap-on heel 22 being cut, scuffed, marred, depressed because of the nature of its material, etc., if used as the template for trimming or scouring both the aforesaid heel seat and heel base components to exact contour and size and also to permit the contouring and sizing operations to be performed without any resort to said finished heel, it is a feature of the invention to use instead a preferably metal template which is attachable to the heel base component 12 in the identical position laterally and longitudinally with respect to the shoe heel as a whole which the finished heel will assume when ultimately attached to said heel base component, and which is thus ideally suited to and capable of serving as a pattern for establishing the exact contour and size to which both said heel seat and heel base components must be trimmed to properly accept the finished heel when it is ultimately attached thereto, which further can be quickly attached to and detached from the heel base, thus to cut machine-out time to a minimum, and finally which can be attached to said heel base in a predetermined axially spaced-apart relation thereto as insures that the operation of contouring and sizing of the heel seat and heel base components is unaffected by variations in the evenness or regularity of the crease between shoe upper and the heel seat portion of the outsole, sometimes also called the rand.

More particularly, the invention provides a template member comprising a template plate proper 26 rigidly affixed to a shoe-rest plate 28. Said template 26 has contour and heel size identical with that of the snap-on heel 22, and it mounts on its relatively upper face a plurality of fastener sockets 30 having function and locational arrangement with respect to one another identical

to that of the aforesaid fastener sockets 24 carried by the snap-on heel 22, thus being complementary to the fastener studs 20 carried by the heel base 12 as aforesaid. Preferably the shoe-rest plate 28 which is rigidly affixed to the under face of the template extends relatively forwardly of the template proper 26 and it may further be narrowed as shown or otherwise formed along its extended side edges so as to be capable of functioning as a handle which facilitates the attaching and detaching of the template.

As further seen in FIG. 4, the placement of the fastener sockets 30 on the upper face of the template proper 26 disposes their working ends well above the upper face of said template, thus to space the template from the attaching face of the heel base 14 to which said template is snapped. As will be later explained, this spacing is of advantage as it permits vertical floating movement of the trimming cutter assembly in accordance with variation in thickness of the rand or heel-seat portion of the outsole or in the regularity of the crease between shoe upper and said heel-seat portion.

The aforesaid template 26 is employed, according to the invention, as a means for guiding a rotating cutter effective to trim (contour and size) the aforesaid heel seat and heel base components of the heel of said shoe to the exact contour and approximate size of the template and thereby of the finished outer heel 22 ultimately to be snapped on to said heel base component, and thereupon for guiding said shoe about a means for scouring the trimmed edge surfaces of said heel seat and heel base, as the term "scouring" is herein used to mean sanding with a fine sand-paper so as to obtain both final heel sizing and a very smooth heel surface devoid of chatter marks, etc. which is suitable to being stained and buffed for final heel finish.

Referring to FIG. 6 illustrating the basic elements making up the trimming or contouring apparatus of the invention, such comprises a machine table 32 having a horizontal top surface on which a shoe may rest as it is being trimmed and also during scouring thereof, through which projects the reduced-diameter, upper end portion 34a of a vertically disposed cutter-drive shaft 34 which is suitably powered by an electric motor or other driving means (not shown) disposed below said table. A rotary, multi-bladed, wheel-type cutter 36 is mounted on and drivingly connected to said drive shaft via a tubular mounting arbor 38 to which the cutter is keyed or otherwise affixed and which is dimensioned so as to be capable of being telescoped on to the reduced upper end of said drive shaft. The arbor, although axially separable therefrom, is drivingly connected to said drive shaft 34 preferably by means of a pair of diametrically opposed drive forks 40a, 40b depending downwardly therefrom and which are receivable in complementary notches 42a, 42b provided in the opposite peripheral portions of the cutter drive shaft just below its upper reduced-diameter end portion 34a, such form of driving connection also permitting limited axial movement of the arbor in upward direction during cutter operation. It will of course be understood that any other suitable axially separable drive connection for driving the cutter arbor 38 from the drive shaft 34 may be substituted.

The aforesaid arbor 38 also mounts a circular, disc-form guide 44 having appreciable axial thickness, and which is disposed just below the cutter, in manner as to be freely revoluble with respect to the arbor and cutter, being mounted on ball-bearings 46. At this point of the description it is noted that the lowermost position of the arbor 38 and thereby of the cutter 36 and freely revoluble guide 44 is determined by an upwardly facing shoulder 48 separating the lower normal-diameter portion of the cutter drive shaft 34 and its reduced-diameter, upper end portion 34a and through which the aforesaid shaft notches 42a, 42b open, which shoulder is disposed just above the level of the machine table 32.

The upper end of the aforesaid arbor 38 mounts a freely rotatable rand-guide 50 (so called because it would bear on a rand if provided) which is adapted to be held in an axially fixed position immediately above the cutter 36 by means of a nut 52 adapted to be screwed to the upper end of the arbor, which is externally threaded for a short-length portion thereof adjacent its upper end so as to be capable of receiving said nut. It will be seen from FIG. 6 that the rand-guide 50 takes the form of a shield-like collar or disc having appreciably greater outer-edge diameter than that of the cutter 36, its outer edge 50a acting much as a circular knife edge consequent to the upper surface of said disc being tapered downwardly-outwardly. As will be hereinafter seen, said outer edge 50a is adapted to extend into the crease between the heel portion of the shoe upper and the extended edge portion of the heel seat 14 of the outsole (or between said heel portion and the heel rand), thereby serving to vertically position the cutter 36 so that its cutting edges will be effective against the outer edge of the heel seat and heel base components of the heel, as is generally indicated in FIG. 6.

The entire cutter assembly, consisting of the arbor 38, the cutter 36, the freely revoluble guide 44, the upper rand-guide 50, and the nut 52, is normally maintained in a lowermost position, as determined by abutment of the lower end of the arbor against the aforesaid drive shaft shoulder 48, by means of a coil-type compression spring 56 disposed in encircling relation about the extreme upper end 34 of the cutter drive shaft which is preferably formed tubular as shown, and which is reactive between the rand-guide securing nut 52 and the under side of a large-diameter head 58 on an end pin 60 which is dimensioned so as to be insertible in the bore of said drive-shaft upper end for detachable securing thereto. Conveniently, the pin securing means may take the form of a bayonet-joint connection comprising diametrically projecting pins 62 carried by the shank of the pin 60 and cooperating J-shaped bayonet slots 64 in the tubular wall of the upper end of the shaft extension 34a and which of course open through the upper edge thereof.

This arrangement provides for limited free-floating movement of the entire cutter assembly against the bias of the spring 56. Means are also provided for positively actuating said cutter assembly in axially upward direction by a limited amount against the bias of spring 56. As more or less diagrammatically shown in FIG. 6, such means comprises a lifter wedge 66 having sliding bearing on the top face of the machine table 32 and adapted for limited movement therealong from its normal retracted position in which it is shown to a more forward or active position in which its wedge-shaped working end 66a wedges in under the freely revoluble guide disc 44 to an extent raising same and thereby the entire cutter assembly a limited amount in upward direction.

To actuate said lifter wedge 66 as aforesaid, it is connected as by pins 68a, 68b extending through elongated slots 70a, 70b provided in the machine table 32 to an under plate 72 having sliding bearing on the under face of said machine table. Normally, said lifter wedge 66 and under plate 72, operating as a unit by virtue of the pin connection therebetween, are maintained in their retracted (rightwise) position by means of a tension spring 74 secured at one end (not shown) to a point on the under side of the machine table and at its forward working end to said under plate 72, as by means of an eye 76 extending downwardly therefrom. Said eye also serves as a means for connecting one end of a cable 78 to said under plate, the cable extending over an idler pulley 80 rotatable in a bracket 82 affixed to the under face of the machine table and thence to a foot treadle (not shown).

By the above arrangement, the entire cutter assembly may be bodily raised by depression of the foot pedal from its normal lowermost position the limited amount necessary to raise the rand-guide 50 to a level such that

its outer edge 50a is disposed slightly above the level of the heel seat portion 14 of the outsole of a shoe supported on said machine table 32 (as indicated in broken lines, FIG. 6). Upon release of the foot treadle, the cutter assembly will lower under the urge of spring 56 to a position determined by engagement of the rand guide with the exposed upwardly facing edge of the heel-seat portion 14 of said shoe. Thereafter, the cutter assembly will "float" in accordance with any variation in thickness of the heel seat component of the heel being trimmed and/or unevenness in the upper surface thereof. Also, the above-described cutter mounting and arrangement provides for simple removal of the cutter assembly as a whole from the cutter-drive shaft 34, for the purpose of changing the revoluble guide to one of greater or lesser diameter, or of sharpening the cutter, or of replacing the cutter assembly with the heel scouring means to be described.

As earlier forecast, the invention provides that after a shoe is put through its heel contouring and sizing operation, i.e. subjected to the action of the cutter 36, it is scoured, i.e. abraded with fine sand-paper (or equivalent) to remove possible chatter marks resulting from the cutter action and to impart a smooth surface to the trimmed heel components preliminary to its final finishing as by staining and buffing, as is conventional. Preferably, the scouring operation is performed immediately following completion of the contouring or trimming operation, and for this purpose the aforesaid cutter assembly may be removed as a unit from the drive shaft 34 (as permitted by the separability of the end pin 60 with respect to the upper end of said drive shaft) and a scouring means whose proper operation is also dependent on the use of the aforesaid template 26, is substituted therefor. Alternately, the machine may be provided with two drive shafts arranged in adjacency, one being or corresponding to the aforesaid drive shaft 34 and the second serving the scouring means, such arrangement also eliminating double handling of the shoe and requiring but a single template.

Illustratively, and referring to FIGS. 7 and 8, the scouring means comprises an endless band of sand-paper 84 trained over a drum-form driven roller 86 and a companion laterally spaced idler roller 88. Preferably, the driven roller is surfaced throughout at least its axial length portion which is engaged by the sand-paper band with a material providing a friction driving surface for said band, such as cork, wood-backed felt, etc., whereas the idler roller 88 may have a conventionally machined surface. The sand-paper band is tensioned whereby it is maintained in friction-driving contact with the driven roller 86 by any suitable endless-belt or band-type tensioning means, which illustratively comprises an arm 90 which mounts the spindle 88a of the idler roller at its approximate mid point and is pivotally connected at its one end to a point on the upper surface of the machine table 32 so as to be capable of swinging towards and away from the driven roller 86, and a tension spring 92 connect-to and biasing the other end of said arm in a direction away from said driven roller. It will of course be understood that the strength of the spring 92 is such that it applies requisite tension on the endless sand-paper belt 84 as to insure the positive drive thereof by the driven roller 86.

Although not shown in detail, it is to be understood that the driven roller 86 is mounted on an arbor corresponding generally to the aforesaid cutter arbor 38 and which is adapted to be telescoped onto the reduced-diameter, upper end portion 34a of the drive shaft and to be drivingly connected to said drive shaft through the provision of lower end driving forks 96a, 96b fitting into the aforesaid notches 42a, 42b of the drive shaft, just as with the arbor 38 of the cutter assembly. The roller arbor also mounts below the roller 86 a freely revoluble disc-form guide 98 and above said roller a top securing nut 100 corresponding to the guide 44 and top nut 52,

respectively, of the cutter assembly. When assembled to the shaft 34 in substitution for the cutter assembly, as in FIG. 7, the roller assembly 86, 98 and 100 is biased to its operative lowermost position in which it is coupled to the drive shaft 34 by means of the aforesaid spring 56 and end pin 60, just as the cutter assembly is so held.

At this point, it is explained that, whereas the revoluble guide 44 of the cutter assembly will in most cases be chosen to have about $\frac{1}{64}$ " larger diameter than that of its cutter 36, with the result that the trimmed heel seat and base will be $\frac{1}{64}$ " oversize as respects the actual size desired in the finished heel product, the diameter of the revoluble guide 98 of the roller assembly is the same as the O.D. of the combination of the driven roller 86 and sanding belt 84 trained thereover. Thus it is contemplated that the sanding belt will bring the heel seat and heel base size down from its approximate $\frac{1}{64}$ " oversize to the exact size desired, at the same time imparting a very smooth surface to the contoured heel edges preliminary to the later staining and buffing operations usually given a shoe heel to finish same.

While it is believed that the heel trimming and scouring method of the invention will be clear from the foregoing description, such are briefly detailed as follows:

A template 36 is made up to a standard of contour and size rendering it suitable as a heel pattern for shoes of any make and size range using the same size heel, and for interchangeable use on each of the right and left shoes of the shoe pairs falling within said size range. Said template will be provided with the female or socket-type fastener elements 30 identical with and arranged similarly to those of the snap-on finished outer heel such as that designated 22 (FIG. 2). Said outer heel will be produced as a finished item having the same contour and size as said template either before or after fabrication of the template and/or the shoe contouring and sizing operation using the same as a heel pattern. The shoe or shoes whose heels are to be contoured and sized will be supplied with rough heel base (12) nailed or otherwise finally fastened in place to the rough heel-seat portion (14) of the shoe outsole (16), and with male or stud fasteners (20) preset in final position on said heel base through the use of appropriate means for fixing their position on said heel base to that of the complementary studs of the finished outer heel. The template 26 is then simply snapped onto the heel base whereupon it assumes a position corresponding exactly to that which the finished outer heel 22 will have when later attached, such exact positioning of course meaning laterally and longitudinally with respect to the shoe heel as a whole since the template will necessarily be spaced downwardly a small distance from the heel base as shown in FIG. 4. Then, the shoe with template attached as aforesaid is placed on the shoe supporting means, i.e. the machine table 32, with its heel portion turned generally towards the cutter assembly assumed to have been or which is now mounted on the drive shaft 34.

The cutter assembly is positively raised by actuation of the foot treadle from its normal position with respect to said table 32 the limited amount necessary to raise the rand guide edge 50a slightly above the level of the upper projecting edge of the heel seat portion of the shoe ready for the heel contouring and sizing operation as aforesaid, whereupon the shoe is moved laterally against the cutter assembly, with the result that the rand guide edge moves into the crease between the shoe-heel upper and the heel seat and the template moves against the freely revoluble disc guide 44 of the cutter assembly. Thereupon, pressure on the foot treadle is released, and the rand guide lowers onto the projecting, upwardly-facing edge surface of said heel seat under the bias of spring 56 effective on the cutter assembly, the spring then serving to cause the rand guide to bear on and ride said edge regardless of

variation in thickness of the heel seat or unevenness of its upper edge surface.

Assuming the cutter to be now positively driven, the shoe is moved by hand generally about the heel axis while maintaining the template in good contact with the guide disc or roller 44, such resulting in the cutter 36 contouring and sizing the heel seat and heel base components of the shoe heel to the contour and approximate size of the template.

In explanation of the latter statement as it pertains to size, it is contemplated that a series of guides corresponding to the guide 44 and having diameters in $\frac{1}{64}$ " increments will be provided, and the guide chosen will be about $\frac{1}{64}$ " larger than the cutter diameter, such resulting in the trimmed heel seat and base being a corresponding $\frac{1}{64}$ " larger than the actual size required in the final heel. The reason for the series of guides having size increments as aforesaid is to compensate for the decrease in cutter diameter inevitably occurring as the cutter is periodically sharpened, and the $\frac{1}{64}$ " oversize is to allow for the small reduction in heel size incident to the scouring operation, which of course removes some of the heel surface material.

Upon completion of the heel trimming operation, and assuming that the shaft 34 also drives the scouring means, the cutter assembly is dismounted from the drive shaft 34 and the roller assembly of the scouring means 84-100 mounted on said shaft in substitution thereof. It is repeated that the diameter of the guide 100 of the roller assembly is the same as the O.D. of the combination of the roller 86 and the sand-paper band 84. This will result in the scouring assembly, through the abrading effect of its sand-paper band, reducing the aforementioned oversize of the heel seat and base components and thus in said components finally having the same contour and size as said template and acquiring a very smooth outer-edge surface ready for the final operation of heel staining and buffing. It will be understood, of course, that during the second stage operation of heel scouring the shoe is rotated about its heel axis and guided in this movement by engagement of the template with the periphery of the guide 98, just as during the first-stage contouring operation. Upon completion of the scouring operation, the template is simply unsnapped from the heel base and the shoe is now ready to receive its finished outer heel as aforesaid.

Since the aforesaid heel seat and heel base contouring and sizing operations are performed independently of and without resort to any physical or direct use of the finished outer heel ultimately to be attached, attachment of said outer heel may be effected at any time following completion of said scouring operation that is practical or convenient, i.e. immediately upon said completion or any time following said completion that fits into or is compatible with a manufacturing schedule.

As many changes could be made in carrying out the above method and constructions without departing from the scope of the invention, it is intended that all matter contained in the above description or shown in the accompanying drawings shall be interpreted as illustrative and not in a limiting sense.

I claim:

1. The method of shoe heel construction, which includes the steps of: providing a template having edge contour and size corresponding substantially exactly to the contour and size of a finished outer heel ultimately to be attached to the heel seat and heel base components of the heel which are already permanently in place on a shoe, detachably securing said template to the heel base component in position corresponding exactly to that which is to be assumed by the finished heel when attached, and contouring and sizing said heel seat and heel base components to the contour and size of the template and thereby of said finished outer heel.

2. The method according to claim 1, wherein the outer

heel is of the snap-on type having snap fastener elements and said heel base is provided with complementary snap fastener elements, and wherein said template is similarly of the snap-on type having snap-fastener elements corresponding in number, arrangement and function to those of the finished outer heel and wherein detachable securement of the template to the heel base component is effected by engaging the snap fasteners of the former with those of the latter.

3. The method of finishing the heel seat and heel base components of a shoe heel, which are already permanently in place on a shoe, to the contour, size and approximate smoothness-of-edge-surface of a finished outer heel ultimately to be attached to said heel base, which includes the steps of providing a template having edge contour and size corresponding substantially exactly to that of the finished outer heel, and through the use of the template as a guide first contouring the edge surfaces of the heel seat and heel base components to the contour of said finished heel and to a size which is slightly greater than that of said template and finished heel, and thereupon scouring the so-contoured edge surfaces by an amount as to reduce the size of said components to that of the template and thereby of said finished heel and in such manner as to provide smooth edge surfaces on said contoured components.

4. The method according to claim 3, wherein the finished outer heel is of the snap-on type which is provided with snap-fastener attaching means and the heel base is provided with complementary snap-fastener means, and wherein said template is similarly of the snap-on type having snap-fastener elements corresponding in number, arrangement and function to those of the outer heel and which further includes the step of detachably securing said template to the heel base prior to the contouring operation by engagement of the snap fasteners of the former with those of the latter.

5. The method according to claim 3, which includes as a step preliminary to that of contouring said heel seat and heel base components the step of detachably securing the template to the heel base in the identical position which the finished outer heel will assume when ultimately attached.

6. The method according to claim 5, and including the further steps of detaching the template from the heel base upon completion of the scouring step, and thereupon attaching the finished heel to said heel base in the position formerly assumed by said template.

7. The method of shoe heel construction which includes the steps of: providing a template of a finished outer heel having identical right- and left-half configuration and size adapting said finished outer heel for use with one or more shoe sizes within a size range, detachably securing said template to the rough heel base component already in place on the portion of the outsole of an existing shoe which constitutes the heel seat component of the heel thereof, and contouring and sizing the rough heel base and the rough heel seat components of the heel of said shoe to the contour and size of said finished heel through the use of said template, whereby finished outer heels having the contour and size of said template may be applied interchangeably to right and left shoes having their heel seat and heel base components contoured and sized as aforesaid and which use the same size of heel as said finished heel.

8. The method according to claim 7, wherein said finished heel is of the snap-on type and the heel base is provided with complementary snap-on fasteners, and wherein said template is similarly of the snap-on type

having snap-on fasteners complementary to and arranged identically with those of said heel base, and wherein detachable securement of the template to the heel base component is effected by engaging the snap fasteners of the former with those of the latter.

5 9. The method of shoe heel construction which includes the step of: contouring and sizing the heel seat and heel base components of a shoe heel already in place according to the contour and size of a template of the finished outer heel ultimately to be attached to said heel base.

10 10. The method of shoe heel construction which includes the steps of: providing a template having contour and size of a finished outer heel ultimately to be attached 15 to the heel seat and heel base components of a shoe heel which are already in place on a shoe and which is further standard for right and left heels and also for a range of heel sizes, and contouring and sizing the heel seat and heel base components according to the contour and size 20 of said template.

11. The method of shoe heel construction according to claim 9, wherein contouring and sizing of the heel seat and heel base components as aforesaid is carried out in two stages, the first stage effecting contouring and sizing 25 to a size which is slightly oversize with respect to template size, and the second stage effecting final sizing to that of the template.

12. The method of shoe heel construction according to claim 9, including the further step of attaching the 30 template directly to the heel base in the identical lateral and longitudinal position which the finished outer heel will assume when attached.

13. The method of shoe heel construction according to claim 10, wherein contouring and sizing of the heel 35 seat and heel base components as aforesaid are carried out in two stages, the first stage effecting contouring and sizing to a size which is slightly oversize with respect to template size and the second stage effecting final sizing to that of the template.

40 14. The method according to claim 1, which includes the further steps of detaching the template from the heel base following completion of the contouring and sizing step, and finally attaching the finished heel to the base in the position thereon formerly assumed by said template.

45 15. The method according to claim 3, which includes the further step of securing a finished outer heel to the heel seat and heel base components in exact edge-surface registry therewith.

16. The method according to claim 7, which includes 50 the further steps of detaching the template from the heel base following completion of the contouring and sizing step and of attaching a finished outer heel to said heel base in exact edge-registry with said contoured and sized heel base and heel components.

55 17. The method according to claim 9, including the further step of, upon completion of said contouring and sizing step, attaching the finished outer heel to said heel base in exact edge-surface registry with the contoured 60 and sized heel seat and heel base components.
